ATTORNEY:

UNITED STATES PATENT OFFICE

JACOB GOODMAN, OF BROOKLYN, NEW YORK, ASSIGNOR TO EMETH FINANCIAL CORPORATION, A CORPORATION OF NEW YORK

HAIR WAVER

Application filed February 9, 1931. Serial No. 514,504.

This invention relates to an improvement in hair wavers or curlers of the type described and shown in Patent No. 1,739,301 granted on December 10, 1929, to Abraham Goodman and myself.

That device comprises a pair of cooperating members between which the hair is engaged and on which the hair is wound, said cooperating members having associated therewith a pivoted wire loop member which is adapted to be swung into position to maintain the hair wound upon the cooperating members, the ends of the wire loop member being inturned and forming a pivot for the cooperating members.

While this construction is simple and inexpensive to manufacture, it is subject to the disadvantage that the pivot may be readily disengaged and that the two cooperating members are not held firmly in place, with the result that they may be displaced laterally relatively to each other and thus have a tendency to cut or injure the hair.

It is the object of the present invention to overcome these disadvantages by the provision of a device of this type in which the cooperating members are so pivoted and fastened as to prevent any objectionable lateral movement.

The invention embodies the provision of a pivot pin which extends transversely through the cooperating members and projects outward slightly at either side thereof, and the provision of securing eyes at the ends of the loop member, said eyes being mounted on the ends of the pivot pin to provide a pivotal mounting for the loop member and to hold the cooperating members against lateral movement, the ends of the pivot pin being headed to maintain the parts in position.

Other novel and distinctive features of the invention will appear from the following description thereof, reference being had to the accompanying drawings illustrating a preferred embodiment, in which:

Figure 1 is a side elevation of the device;

Fig. 2 is a plan view thereof; and,

Fig. 3 is an enlarged cross-sectional view taken on the line 3—3 of Fig. 1.

Referring now to the drawings, the device

comprises two cooperating members 10 and 11 pivoted together by means of a pivot pin 12. The member 10 is of tubular form, and the member 11 is of concavo-convex cross section so formed as to fit over the member 10. These members are preferably made of light weight sheet metal, such as aluminium sheeting. Said members 10 and 11 are formed with ears 13 and 14 having perforations through which the pivot pin extends. The ears 13 and 14 are located considerably nearer one end of the cooperating members than the other so as to provide a short finger grip portion 15 at one side of the pivotal point and a relatively longer hair winding portion at the other side thereof. A suitable spring 16 is disposed between the finger grip portions, which spring acts normally to press the two cooperating members together.

17 is a loop of wire having its sides extending in spaced relation to the hair winding portion of the members 10 and 11. Securing eyes 18 are formed at both ends of the wire loop 17, said eyes being preferably formed by coiling or bending the ends of the wire.

The pivot pin 12 passes through these eyes and is headed at both ends 20 to fasten the parts in position so that the loop may be swung toward or away from the cooperating members.

This mode of construction fastens the parts firmly together in such manner as to prevent objectionable lateral displacement of the members 10 and 11 relatively to each other. It will be seen that should the member 11 become laterally displaced in relation to the member 10 it will no longer fit over the latter but one of its edges will bear down on said member thus tending to cut the ends of the hair, particularly as the spring 16 acts to urge the members together with considerable force.

In operation, the ends of the hair are gripped between the members 10 and 11 and the hair is then wound or coiled thereon by a rotary movement of the device. After the hair has been wound or coiled on said members, the loop 17 is swung into operative

position to bind and maintain the hair in place.

It is to be understood that modifications in the details herein described may be made 5 within the scope of the appended claim.

What I claim is:

A hair waver comprising two cooperating members between which the ends of the hair are engaged and about which the hair is 10 wound, resilient means between the members at the outer ends thereof to urge the opposite ends of the members toward one another, said members having pairs of overlapping ears at their sides and between the ends thereof, a 15 fixed pin extending transversely through said ears and having headed ends which latter are spaced from the outer ears, and a loop of wire for holding the hair wound on said members, said loop having each of its ends 20 coiled around the pivot pin to support the loop for independent pivotal movement relative to said members, the heads of the pin being tightly engaged with the coiled ends of the loop so as to tightly hold the coils against 25 the adjacent ears and the latter against one another.

JACOB GOODMAN.
